The ornamental design for a tool holder, as shown and described.

DESCRIPTION

FIG. 1 is a perspective view a tool holder showing our new design;

FIG. 2 is a left side elevational view showing the design for the tool holder of FIG. 1;

FIG. 3 is a right side elevational view showing the design for the tool holder of FIG. 1;

FIG. 4 is a top elevational view showing the design for the tool holder of FIG. 1;

FIG. 5 is a bottom elevational view showing the design for the tool holder of FIG. 1;

FIG. 6 is a front elevational view showing the design for the tool holder of FIG. 1; and,

FIG. 7 is a rear elevational view showing the design for the tool holder of FIG. 1.

In FIGS. 1-7, the broken lines showing of various items including (i) the coupling component at the rear portion of the tool holder (FIGS. 1-7), (ii) the support structure at left side portion of the tool holder (FIGS. 1-2 and 4-7), and (iii) the support structure at the bottom portion of the tool holder (FIGS. 1-3 and 5-7) is for illustrative purposes only and forms no part of the claimed design.
